(57) **CLAIM**

The ornamental design for a mobile exercise apparatus, as shown and described.

DESCRIPTION

FIG. 1 is a perspective view of a mobile exercise apparatus showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a perspective view of the mobile exercise apparatus with a base portion.

The broken lines showing a base portion in FIG. 8 depicts environmental subject matter, which form no part of the claimed design.
